H. H. EDWARDS.
COMBINED BOOK REST AND RECEPTACLE.
APPLICATION FILED SEPT. 11, 1911.

1,035,430.

Patented Aug. 13, 1912.

UNITED STATES PATENT OFFICE.

HELENA H. EDWARDS, OF PASADENA, CALIFORNIA.

COMBINED BOOK REST AND RECEPTACLE.

1,035,430.

Specification of Letters Patent. Patented Aug. 13, 1912.

Application filed September 11, 1911. Serial No. 648,749.

To all whom it may concern:

Be it known that I, HELENA H. EDWARDS, a citizen of the United States, residing at Pasadena, in the county of Los Angeles 5 and State of California, have invented new and useful Improvements in Combined Book Rests and Receptacles, of which the following is a specification.

This invention relates to improvements in 10 combined book rests and receptacles and it is particularly adapted for the holding of books in open condition when they are to be used and when the books are not in use the device is adapted to be folded to inclose 15 and protect the same.

It is an object of the invention to provide a book rest and receptacle which is adapted to be unfolded and set up so as to receive and hold in position for reading, certain 20 books and pamphlets which are to be read in connection with each other.

It is an object also of the invention to provide a book rest made up of folding casings and having a locking member interposed 25 between them adapted to hold them in open and book supporting position.

In the accompanying drawing forming a part of this specification, Figure 1 is a perspective view of the improved book rest 30 and receptacle when in opened position and in readiness for use as a book rest. Fig. 2 is a perspective view of the said device when it is in closed or folded position for forming a receptacle for holding books or other 35 articles. Fig. 3 is an enlarged vertical sectional view taken transversely through the book rest and receptacle when in folded position, the said section being taken upon the line 3—3 of Fig. 2. Fig. 4 is an enlarged 40 detail sectional view taken upon the line 4—4 of Fig. 3.

The device forming the subject matter of the present invention is designed to afford a folding book rest, the members of which 45 may be opened and locked in unfolded position to receive and hold books in open position as when reading or studying the same. The device is especially well adapted for use in connection with books and pamphlets 50 that are read in connection with each other as for instance the Bible, the Christian Science publication, *Science and Health*, and the pamphlet or quarterly that is read by any in connection therewith, the object 55 being to hold all three of the said works in open position at the same time. The

device is also of such shape and size as to just receive and inclose the said books and pamphlets that may be read in connection with each other when they are not in use, 60 the said device acting as a receptacle and convenient case for the said books whether they are to be laid aside and protected from dust or damage or whether they are to be carried from place to place. 65

The details of the invention will now be more particularly described, reference being had to the said drawing, in which—

5 indicates back sections of the book rest which are formed with end flanges 6 and 70 side flanges 7, the said flanges forming closing edges for the device. The inner ends of the back sections 5 are hinged to a connecting hinge member 8. The two back sections 5 thus each have a hinge movement 75 with respect to the hinge member 8, and the said hinge member closes the space between the two sections at one end when they are folded into the position shown in Fig. 2. The hinge section 8 is formed with a guide- 80 way 9 to receive a slide 10 and the said slide carries a locking member 11 which is pivoted to the slide at 12, so that it may be turned parallel with the slide when the device is to be folded, and at right angles 85 to the slide when it is to lock the parts in open position as shown in Fig. 1. As shown in said Fig. 1 also the locking member 11 is provided with end projections 13, which are adapted to extend 90 through slots 14 formed in the flanges 7 of the back sections and thus hold the back sections in alinement with each other when they are open. The said locking member 11 is preferably formed of material folded so 95 as to provide a pamphlet or book receiving space 15 between the sides thereof as shown in Figs. 1 and 4. The end portions of the material thus doubled which project above the flanges 7, together with the central portion 16 which is also allowed to project above the flanges 7, constitute receiving and holding means for the edges of a pamphlet or other publication which may be mounted upon the rest. The slide 10 because of its 100 relation to the pivotal connection with the locking member 11, will project above the same to form a back support for the pamphlet or other publication mounted in the said receiving space 15. When the parts are in 110 this position as shown in Fig. 1 the device cannot be folded. When it is intended to

fold the device, the slide 10 is moved downwardly in the guideway 9, carrying the locking member 11 with it, until the said locking member can be turned upon its pivot 5 to the position shown in Fig. 3, after which the back sections 5 may be brought together and the whole device thus folded and arranged in compact form. A latch or clasp 17 hinged to one of the said back sections 10 17 is adapted to be brought over the edges of the two sections as indicated in Fig. 2 for holding the parts in folded position. The rest is preferably provided with means for supporting it in approximately 15 upright or inclined position to facilitate the reading of the literature placed upon the support and for this purpose the ends of the back sections 5 are provided with hinge bars 18 which are pivoted at 19 to the 20 end flanges 6 and each of said bars is provided with notches 20 adapted to receive a headed stud 21 carried by a bar 22 which is also pivoted upon the flange 6, one being provided for each back section 5. The bars 25 22 are pivoted to the back sections at 23 a sufficient distance from the pivot points 19 to permit of the said bars 22 being used as braces to hold the bars 18 in extended position as shown in Fig. 1. In this manner 30 supporting foot portions or braces may be provided at each end of the device for holding it in set up form. The bars 18 and 20 are adapted to be folded, the said bars being formed with off set portions as shown 35 in Fig. 1 so that they will fold over the bars 22. The said bars 18 are also provided with notches 24 to receive the studs 21 when the parts are in folded position as illustrated in Fig. 2. The ends of the bars 40 18 are arranged to extend beneath overhanging flanges 25 and 26 formed upon the outer ends of the back sections 5. The clasp 17 is adapted to fit over the said bars when they are in folded position as will be 45 clearly understood by reference to Fig. 2. The said parts are thus admirably adapted for supporting a book rest in open inclined position for receiving the literature to be supported thereon and yet are capable of 50 folding into very compact form when closed as a receptacle, ample room being provided inside for the reception of the literature or books which the book rest is adapted to support.

55 Of course it will be understood that the parts of the rest may be made of metal or

of any other suitable material and may be suitably designed and decorated within the spirit of the invention. The decorations provided upon the hinge member 8 may be 60 so formed that projections forming parts thereof can be offset inwardly and outwardly, to form the guiding groove provided for the reception and movement of the slide 10. 65

What I claim is:—

1. A combined book rest and receptacle, comprising a centrally disposed section, back sections hinged thereto, and a slidable locking means being mounted on said central section, said locking means being movable longitudinally on said central section and adapted when moved out of its normal position to engage and lock the back sections in rigid relation to said central section. 70

2. A combined book rest and receptacle, comprising back sections, a hinge section interposed between them permitting of their being folded to form a receptacle, a locking means engaging said back sections for holding said sections in unfolded position and end projections disposed upon said locking means affording a support for literature, books or the like. 75

3. A book rest and receptacle comprising back sections, a hinge connecting section joining them, a latch member movably mounted on the hinge section, and having projections adapted to hold literature in open form, and means for holding the device in approximately vertical or inclined position when acting as a book rest. 80

4. A combined book rest and receptacle, comprising back sections having edge flanges, hinge means interposed between the 90 said sections and permitting of their being folded to form a receptacle, means for holding them in unfolded position, and adjustable end supports comprising notched bars, and bars having detents adapted to engage the notches of said notched bars whereby the device when open may be supported in proper position for the reading of literature mounted thereon. 100

In witness that I claim the foregoing I 105 have hereunto subscribed my name this first day of September, 1911.

HELENA H. EDWARDS
